(57) **CLAIM**

The ornamental design for a medical equipment bag, as shown and described.

DESCRIPTION

FIG. 1 is a front-left perspective view of a medical equipment bag, shown with the flaps and straps not exposed;

FIG. 2 is a rear-right view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front-left perspective view of the medical equipment bag, shown with the flaps and straps exposed;

FIG. 10 is a rear-right view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines depict portions of the article that form no part of the claimed design.
